UNITED STATES PATENT OFFICE.

JOSEPH J. REINA, OF NEW YORK, N. Y., ASSIGNOR OF ONE-HALF TO RAYMOND F. WELCH, OF NEW YORK, N. Y.

REMOVABLE INSOLE FOR SHOES.

Application filed January 13, 1923. Serial No. 612,430.

To all whom it may concern:

Be it known that I, JOSEPH J. REINA, a citizen of the United States of America, residing at New York, N. Y., have invented 5 a new and useful Removable Insole for Shoes, of which the following is a specification.

My invention relates to a new and improved removable insole for a shoe. The 10 object of the invention is to provide, as an article of manufacture, an insole for a shoe, which insole is so constructed that it may be easily inserted and removed, and which when in place will operate to cushion all 15 parts of the sole of the foot to relieve such pressures as produce painful callouses. To one having such callouses the use of my new insole affords instant relief and also results in the gradual disappearance of said callouses.

In the accompanying drawings:

Fig. 1 is a plan view of the upper side of an insole constructed to embody my invention.

25 Fig. 2 is a plan view of the lower side.

Fig. 3 is a longitudinal section.

1 represents a smooth coating for the upper surface of the insole. 2 represents the main body of said insole, which is made 30 from "sponge" rubber of substantially greater thickness than the surface coating 1. This sponge rubber main body furnishes, in addition to a multitude of soft cushioning air cells, a relatively rough lower 35 surface which, when the insole is placed in a shoe, clings to the leather insole so that it will not work out of place while in use. The smooth surface layer 1 may be made integral with the sponge rubber body 40 if desired. I am aware that sponge rubber has heretofore been employed in the construction of insoles and shoe soles, but in all such instances so far as I am informed both surfaces of the sponge rubber have 45 been covered with smooth imperforate layers of rubber or other suitable coating material which not only adds to the weight and cost but which also eliminates the relatively rough non-slipping surface of the 50 sponge rubber from coming in contact with the leather shoe insole for the purpose above described. In prior cases, the covering of both surfaces of the sponge rubber with relatively smooth imperforate sheets or coatings 55 has prevented the user from thorough-

ly cleaning such devices. It is obvious that in the use of insoles, formed in part of sponge rubber, perspiration will gradually work into the pores or cells of the same, and it is equally obvious that much difficulty will be experienced in thoroughly washing or cleansing the same when only the edges are exposed as in the prior art devices. On the contrary, in the form shown and described herein all parts of the sponge rubber body are accessible for thorough washing and cleansing. I have also found that by providing a surface coating on one side only of the removable insole the extreme flexibility and elasticity 60 of the sponge rubber body is in no substantial degree impaired or lessened; whereas with spaced surface coatings secured on the opposite surfaces of the insole the truss-like formation thus produced renders the 65 insole much less flexible and hence it will not as readily conform to all of the curves and irregularities of the shoe insole and of the sole the foot as will my improved device. Again, by covering only one surface of the 70 sponge rubber body, the weight of the insole is substantially lessened. Again, by coating on one side only of said sponge rubber body the cost is substantially lessened. Again, an insole constructed in accordance 75 with my invention may be very easily trimmed around its edge to shape it accurately to the insole of the particular shoe with which it is to be used. It is manifest that all of these features are of great ad- 80 vantage to the user.

I preferably form the surface coating 1 by applying to one surface of the main body 2, a thin layer of rubber cement or the like, over the surface of which I apply a suitable quantity of a finely divided, friction reducing powder such as chalk or soapstone; all of which, when dried, forms a substantially integral part of the main body 90 2. While, of course, other coatings may be 100 substituted, I have found that a coating constructed substantially as above has many advantages and is much to be preferred, for example it eliminates the necessity of applying a separate sheet of rubber or the 105 like to one face of the sponge rubber to secure a smooth contact for the sole of the foot. While this addition produces a smooth effect, the stick clinging feeling of rubber is eliminated and the effect of leather 110

is more closely approximated. This filler also serves to penetrate the pores of the sponge rubber on one side of the insole, and prevents wear and disintegration thereof, thereby adding to the durability of the article.

a main body of sponge rubber of substantial thickness having large pores throughout its surface, a filler material filling the pores in one surface of said body said filler material itself forming a smooth tread surface.

What I claim is:

A removable insole for shoes, comprising

JOSEPH J. REINA.
